UNITED STATES PATENT OFFICE.

AUGUST SUNDH, OF HASTINGS-UPON-HUDSON, NEW YORK.

GATE AND HINGE.

1,218,715.

Specification of Letters Patent. Patented Mar. 13, 1917.

Application filed January 11, 1915. Serial No. 1,529.

To all whom it may concern:

Be it known that I, AUGUST SUNDH, a citizen of the United States, and resident of Hastings-upon-Hudson, in the county of Westchester and State of New York, have invented a certain new and useful Gate and Hinge, of which the following is a specification.

My invention relates to a combined gate and hinge in which a section of the hinge forms part of the framework of the gate.

An object of the invention is to provide a construction in which the hinge is located at the side of the post to which the gate is hinged with a minimum space between the gate and the post.

A further object is to embody the gate hinge in the frame of the gate itself, thereby obviating the need of a special device to connect the hinge to the gate. The hinge also takes the place of an elbow or other binder for the framework of the gate and makes a strong, compact, and inexpensive construction.

Other features and advantages will appear hereinafter.

The present application discloses certain features and principles of construction also disclosed in my co-pending application, Serial No. 1528, filed January 11, 1915.

The construction and operation of the hinge itself is substantially the same as that set forth in Patent No. 1,155,452, granted to me October 5, 1915.

In the accompanying drawings,—Figure 1 is an elevational view of a gate and fence constructed in accordance with the principles of my invention. Fig. 2 is a sectional elevation on a larger scale of the lower gate hinge and associated parts. Fig. 3 is a sectional plan view showing a bracket connecting the hinge and post. Fig. 4 is a fragmentary sectional view illustrating a modified form of connection between the gate frame and hinge.

The gate 1 is connected to the fence post 2 by upper and lower hinges 3 and 4, and may swing in either direction from its closed position in which it is held by a latch 5. The upper hinge 3 may be in the form of a strap rigidly secured by bolts or rivets to the post 2, and having a loose connection with the gate frame to permit the latter to rotate and move up and down in the hinge as the gate swings.

The lower hinge 4 as herein shown is a

gravity operated hinge such as fully disclosed in the patent above referred to. This hinge comprises a section 6 carried by and forming part of the gate, said section being in the form of a casing telescoping with and inclosing a stationary hinge section 7. The rotatable member 6 comprises a cam 8 having downwardly and outwardly divergent cam bearing surfaces to run on an anti-friction roller 9 journaled on a pin supported in the stationary hinge member 7. When the gate swings open in either direction the cam runs up on the roller 9, thereby lifting the gate, so that when the gate is released it will automatically return by gravity to closed position. A pintle 10, which may be fixed to the cam 8, extends vertically downward in a socket formed by an inner tube 11 and a downward extension 12 of the stationary hinge section. The cam 8 may be formed with a squared head 13 to enter a squared socket 14, the walls of the socket being somewhat divergent and forming as shown, small angles with the head 13 to permit a slight tilting of the gate in its own plane relative to the cam and pintle. This arrangement permits automatic adjustment of the gate to equalize the lateral pressure on the hinges and also prevents undue lateral strain being thrown on the pintle if the latter is not in exact vertical alinement with the axis of rotation of the gate.

The hinge section 7 is rigidly secured to the post 2 by means of a bracket 16 which may be formed integral with the extension 12. The outer end of the bracket may form one jaw, and a hinged piece 17 the other jaw of a pair of jaws which surround the post 2 and are clamped thereto by a bolt 18. The stationary hinge section 7 forms a receptacle containing a lubricating oil 19 in which the bearing surfaces of the hinge are immersed. A restricted passage 20 in the form of a longitudinal groove in the pintle 10 allows a restricted flow of the lubricant and thereby effects a dash pot action to retard the gate as it swings closed.

The hinge member 6 forms a binder or tie piece uniting the vertical rod 21 and the horizontal rod 22 which form part of the framework of the gate. To this end the section 6 is formed with integral tubular projections or nipples 23 and 24 which are internally threaded to receive the screw threaded ends of the tubular frame rods 21 and 22 respectively. It will be noted that by

means of this construction, the gate is brought quite close to the post 2 instead of a wide gap being left between the gate and post as would occur if the hinge were not a part of the gate frame but attached thereto by a bracket or other means. The hinge itself takes the place of an elbow, T joint, or other connection at the corner of the gate frame, and produces a rigid, substantial and economical construction. The hinge member 6 may be formed with an integral rib 25 provided with openings 26 forming a means for attaching the wire work 27 of the gate to the hinge.

Fig. 4 shows a modified form of connection between the hinge member 6 and the gate. As here shown, the tubular rods 21 and 22 are internally threaded to receive the solid plugs 23' and 24' projecting from the hinge section 6 and formed with screw threads to connect with the gate frame.

Although the hinge 4 which forms a binder for the gate frame is shown at the lower corner of the gate and the strap hinge 3 at the upper corner of the gate, this particular location and arrangement of the hinges might be modified.

Various modifications other than those herein mentioned may be resorted to within the spirit and scope of my invention.

What I claim is:—

1. The combination of a gate, a support, and hinge mechanism by which the gate is suspended from said support, said gate comprising a frame having an upright member 35 and a transverse member at the lower end of the gate, said hinge mechanism comprising a hinge part secured to said support, and a coöperating rotatable hinge part comprising

a cylindrical casing closed at the top and open at the bottom to receive said first mentioned hinge part which projects upward within the casing, said casing having nipples extending upwardly and laterally respectively from its closed top and side, said nipples having screw-threaded connection with the adjacent gate frame members, whereby said rotatable hinge part forms a binder rigidly uniting the said members of the gate frame, the axis of rotation of the gate being in said upright frame member. 40

2. As an article of manufacture, a hinge part comprising a cylindrical casing having an integral closed end, the other end being open, and integral, screw-threaded nipples, 55 one projecting endwise from said closed end, and the other projecting laterally from the casing adjacent the open end thereof, said nipples forming means for attachment of the hinge part to the frame work of a gate. 60

3. As an article of manufacture, a hinge part comprising a cylindrical casing having an integral closed end, the other end being open, and integral, screw-threaded nipples one projecting endwise from said closed end, 65 and the other projecting laterally from the casing adjacent the open end thereof, and an integral rib on the outer face of the casing extending from one to the other of said nipples and provided with a series of openings. 70

Signed at New York city in the county of New York and State of New York this 8th day of January A. D. 1915.

AUGUST SUNDH.
